UNITED STATES PATENT OFFICE.

HARRY WARD LEONARD, OF BRONXVILLE, NEW YORK.

ELECTRIC-CIRCUIT CONTROLLER.

No. 914,357.

Specification of Letters Patent.

Patented March 2, 1909.

Original application filed November 30, 1901, Serial No. 237,653. Divided and this application filed April 6, 1906.
Serial No. 310,201.

To all whom it may concern:

Be it known that I, HARRY WARD LEONARD, a citizen of the United States, residing at Bronxville, in the county of Westchester 5 and State of New York, have invented certain new and useful Improvements in Electric - Circuit Controllers, of which the following is a full, clear, and exact specification.

This application is a division of my pending application filed November 30, 1901, Serial No. 84,188, renewed December 20, 1904, Serial No. 237,653, granted April 10, 1906, Patent No. 817,719, and relates generally to controlling switches and has a particular application to motor starting rheostats, or rheostats employed with electric motors or other electrical translating devices, in which the resistance is employed 10 not for regulating the energy supplied to the motor or other translating device, but mainly for gradually raising the energy at the terminals of the translating device to the full electromotive force. My invention is 15 also of importance where regulating resistances are used and to prevent their improper operation. I have found in practice that such rheostats are frequently damaged by holding or permitting the contact lever to 20 remain on the initial or starting contact or contacts near the same with all the resistance of the rheostat or a considerable portion thereof in circuit. I have also found that operators frequently close the circuit 25 at the initial or starting contact of the rheostat and then return the lever to the idle position, thus drawing an arc at the initial contact. This also damages the rheostat. I have also found that operators sometimes 30 close the main circuit when the resistance controlling device, which might be used as a regulator, is in an intermediate position. This, of course, allows an excessive and 35 damaging flow of current.

The main object of my invention is to 40 devise a starting rheostat or controller, or to provide the present type of starting rheostats with a controlling device, which will prevent this improper handling of such 45 rheostats.

The full torque current is the current 50 which the motor takes when developing its full rated horse power. In starting any motor, it becomes necessary to produce a 55 torque larger than that due to the full torque

current because the motor and the load have to be accelerated and during the period of acceleration, a larger current will be required than that necessary after the motor has been accelerated to full speed. In the 60 manufacture of motor starting rheostats, it is common practice to have such a resistance in the rheostat that the current which will flow when the motor is at rest and the first contact is made at the rheostat, will be fifty 65 per cent. larger than the current taken by the motor when producing its normal full torque. In other words, this starting accelerating current is fifty per cent. larger than the full torque current, that is, it is one hundred and 70 fifty per cent. of the full torque current.

In order to prevent the burning at the initial contact of the rheostat, due to the closing of the circuit upon insufficient surface, or due to the backward movement of 75 the contact lever after making the first contact, which results in the formation of an arc due to the full electromotive force and one hundred and fifty per cent. of the full torque current (when the motor has no 80 counter electromotive force), the rheostat should be provided with an auxiliary switch, by which the circuit is quickly closed upon an ample surface, and which switch will open the circuit with a snap-action when the contact lever is returned to the initial position. This auxiliary switch should be beyond direct hand control in opening, and may be 85 mechanically or electrically controlled by the rheostat contact lever or controlling 90 switch.

In my original application, I have disclosed two forms of my invention in which the auxiliary switch is mechanically controlled. The present application relates 95 more particularly to forms in which the control of the auxiliary switch is by electrical means.

My invention includes various other improvements and advantages which will be 100 understood from the following description and accompanying drawing.

In the accompanying drawing, the figure 105 is a diagrammatic view showing one form of my invention.

Referring to the figure, there is mounted on a suitable base (not shown) a series of contacts *a*, to which the sections of the resistance *a'* are connected. This resistance, 110 it will be understood is arranged in any

suitable manner beneath the base or within a casing, and the sections of resistance will be insulated from each other, and in some instances provided with means for absorbing 5 the local energy developed therein.

B is a switch in the form of a rheostat contact lever pivoted on the base. The supply conductors are indicated at P and N, and the translating device controlled is shown as a 10 motor M. The auxiliary switch C is shown in the form of a brush switch. A controlling coil for the switch is shown at O², which coil is connected between conductor P and a contact o² with which the insulated short 15 arm b² of lever B makes contact when in contact with any of the rheostat contacts a from the second to the final contacts, but not when in contact with the initial contact. Switch C is provided with a rod z 20 which breaks the arc on carbon contacts z'. This switch is mounted on a vertically sliding rod z², provided at its upper end with a stirrup z³ within which works a foot o³ secured to the lower end of rod o⁴ projecting 25 from the core or plunger of coil O². The vertically sliding rods z² and o⁴ work in suitable guides and the lower end of rod z² is rectangular and works in a correspondingly shaped bearing to hold switch C in alinement 30 with its stationary contacts.

The rheostat lever B is shown in its second position, and the circuit to coil O² is closed and its core is drawn up and switch C is closed. If now the operator returns lever 35 B to the initial position, coil O² will become demagnetized and its plunger will drop striking a blow to the stirrup, the force of which and the tension of the brush switch, will drive the switch downward and open the 40 circuit to the rheostat and motor. When the lever B is moved forward, closing the circuit again at contact o², the plunger of coil O² will rise, and through the engagement of foot o³ and stirrup z³, switch C will 45 be closed. It will be understood that upon failure of the line voltage or upon the occurrence of abnormally low voltage, the current in coil O² will cease to flow or become so weak as to be unable to sustain the weight 50 of its core or plunger which would thereupon drop and automatically effect the opening of switch C. This coil and the switch therefore serves as a means for protecting the circuit from no-voltage conditions.

55 It will be noted that I have indicated a motor M in the drawing having a shunt field winding, and that the supply circuit to both the armature and shunt winding is opened by means of the automatic switch 60 in the main circuit. Also, that when the circuit is opened, the armature and field are closed on themselves giving a closed circuit for the field discharge.

It is evident that my invention may be 65 embodied in various forms of construction,

and that I am not limited in the scope thereof except as indicated in the following claims.

Having thus described my invention, I declare that what I claim as new and desire 70 to secure by Letters Patent, is,—

1. The combination of a motor rheostat, a circuit breaker, a coil for holding said circuit breaker closed, and circuit connections controlled by the movement of the resistance varying element of said rheostat for controlling the opening of said circuit breaker by controlling the current in said coil. 75

2. The combination of a motor rheostat, a circuit breaker, a coil for holding said circuit breaker closed, and circuit connections controlled by the movement of the resistance varying element of said rheostat for controlling the closing and opening of said circuit breaker by controlling the current in said coil. 80

3. The combination of a motor rheostat, a circuit breaker, a coil for holding said circuit breaker closed, and a contact engaged by the resistance varying element of said rheostat 90 at or near its initial position for controlling the opening of said circuit breaker by controlling the current in said coil.

4. The combination of a motor rheostat, a circuit breaker, a coil for holding said circuit breaker closed, and a contact engaged by the resistance varying element of said rheostat at or near its initial position for controlling the closing and opening of said circuit breaker by controlling the current in said coil. 95

5. The combination of an electric motor having a shunt field winding, a starting resistance, the motor armature, field winding, and starting resistance being connected in a permanently closed local loop, a movable element for varying said resistance but not adapted to open the circuit, a switch in series with the motor, a no-voltage coil for holding said switch closed, and a contact device for controlling the current in said coil and controlled by the movement of said element. 100

6. The combination of a supply circuit, an electric motor, an armature rheostat for said motor having no open circuit position, an automatic switch for closing and opening the 115 armature circuit of said motor across said supply circuit, said automatic switch having a tendency to move to its open position by gravity, an electromagnetic coil for normally holding said switch closed against gravity, and means for normally controlling the closing of said switch when a protective amount of resistance is in series with the motor armature and the opening of said switch after said resistance has been inserted. 120

7. The combination of an electric motor, an armature rheostat, a vertically movable automatic laminated contact switch in series with the motor armature and said rheostat, an electromagnetic coil for automatically 130

5 closing said switch when energized and which upon no-voltage allows the switch to be moved by gravity to open position, a contact device for controlling the magnetization and demagnetization of said coil, and means for controlling said device by the movable element of said rheostat.

8. The combination of a controlling rheostat, a switch in series with said rheostat, a 10 coil for automatically closing said switch and for holding said switch closed, and a contact device controlled by the movement of the movable element of said rheostat for making and breaking the circuit of said coil only 15 when the resistance of said rheostat is in circuit.

9. The combination of a motor, a hand-operated rheostat in series with the motor armature, a switch in series with said rheostat and armature, a coil for closing said switch automatically, and for holding said switch closed, and means for closing and opening the circuit of said coil for closing and releasing said switch, said means being controlled by the movement of the movable element of said rheostat when said element is at or near its initial position.

10. The combination of a controlling rheostat, a switch in series with said rheostat, a 20 coil for automatically closing said switch and for holding said switch closed, and a contact device controlled by the manual movement of the movable element of said rheostat for making and breaking the circuit of said coil only when the resistance-controlling movable element is at or near its initial position.

11. The combination of a controlling rheostat, a switch in series with said rheostat, electro-magnetic means for controlling the automatic closure of said switch and for holding said switch closed, and a contact device controlled by the movable element of said rheostat for making and breaking a controlling current for said means when the resistance-controlling movable element is at or near its initial position.

12. The combination of a motor rheostat, a circuit breaker in series therewith, electrical means controlled by the movement of the movable element of said rheostat for effecting the closure of said circuit breaker against the action of gravity, said switch being automatically moved by gravity to a protective position upon the occurrence of no voltage.

13. The combination of resistance-varying means, an automatic switch, said switch being acted upon by gravity for securing the automatic opening and having electrical 60 means for controlling the automatic closure of said switch, and electrical means for protectively relating said resistance - varying means and said switch.

14. The combination of an electric motor, 65 a resistance having a movable element for

varying said resistance, an automatic switch comprising a laminated main contact and an auxiliary final break contact, said element, switch and motor armature being connected in series with each other, and means controlled by the movement of said element for controlling the automatic movement of said switch.

15. The combination of a supply circuit of constant electromotive force, an electric 70 motor, an armature rheostat, the said rheostat and motor armature and field winding of the motor being connected in a closed local circuit, a switch for connecting said local circuit to the supply circuit, and means comprising a coil for automatically closing and opening said switch, the magnetization and de-magnetization of said coil being controlled by the to-and-fro movement of the movable element of said rheostat and thereby causing the closing and opening of said switch.

16. The combination of a motor-controlling rheostat having a movable element for varying the resistance in the circuit, a contact made and broken by the movement of said element, a coil energized and deenergized respectively in response to the making and breaking of said contact, and means controlled by said coil for controlling the current 95 through said rheostat.

17. The combination of a circuit-controlling rheostat having a movable resistance-varying element, means for causing an auxiliary electrical contact to be made by the 100 movement of said element to a certain position and to be broken by its movement in a direction to insert resistance, an electro-responsive winding, the current in which is affected by the making and breaking of said 105 contact, and a switch responsive to no voltage controlled by said winding.

18. The combination of a rheostat having a movable element for varying the resistance, a switch in series therewith, magnetic restraining means for holding said switch in closed position, and electrical means for releasing said restraining means to automatically control the opening of said switch by the movement of said element when substantially all of the resistance is in circuit.

19. The combination of constant electromotive force supply means, an electric motor having a field winding energized independently of the working armature current, a controlling resistance for the motor, connections forming a permanently closed local loop including the motor armature, said resistance and field winding, a protective switch, said local loop and said switch being connected 120 in series with each other across said mains, an electro-responsive winding for automatically causing the closing of said switch, said winding being connected in a branch circuit across said mains in parallel with said loop.

20. The combination of an electric motor, a resistance-controlling movable element in series with the armature of the motor, a functionally related automatic switch in series with said armature and said element, and means for automatically closing and opening said switch upon movement of said element by the operator, said switch being automatically responsive to no voltage in its opening movement.

21. The combination of a motor, a switch in series with the motor armature, a motor controller having a resistance varying movable device and functionally related manually controlled auxiliary contact means controlled by the movement of said device, an electro-magnetic coil for controlling the au-

tomatic closure of said switch, said coil being responsive to no voltage to control the automatic opening of said switch upon occurrence of no voltage, and said contact means and said coil being functionally related to cause the automatic closing movement of said switch when said resistance varying device is in a certain position and also to control the automatic opening movement of said switch at the will of the operator. 20 25

In testimony whereof, I affix my signature in the presence of two witnesses.
